UNITED STATES PATENT OFFICE.

VERNON DURBIN, OF NEWTON, MASSACHUSETTS, ASSIGNOR TO THE HOLTZER-CABOT ELECTRIC COMPANY, OF ROXBURY, MASSACHUSETTS, A CORPORATION OF MASSACHUSETTS.

LOUD SPEAKER.

Application filed October 20, 1924. Serial No. 744,542.

To all whom it may concern:

Be it known that I, VERNON DURBIN, a citizen of the United States, residing at Newton, in the county of Middlesex and State of Massachusetts, have invented certain new and useful Improvements in Loud Speakers; and I do hereby declare the following to be a full, clear, and exact description of the invention, such as will enable others skilled in the art to which it appertains to make and use the same.

The present invention relates to an improvement in loud speakers.

The object of the invention is to reorganize and improve the construction of loud speakers, and to this end the invention consists in the improvement hereinafter described and particularly defined in the claims.

20 In the accompanying drawing illustrating the preferred form of the invention Fig. 1 is a sectional elevation of the base of the instrument, and Fig. 2 is a bottom plan of the same.

25 The illustrated embodiment of the invention is described as follows: The base 10 consists of a casting or bell of inverted dish form. It is a heavy casting provided at its lower edge with a thickened lip 11 having a groove in its bottom to receive a leather cushion ring 12 upon which the base rests when it is standing on a support. Projecting upwardly from the bell is a horn holder 13 which receives the usual loud speaker horn. A throat 14 smaller than the inside of the horn holder connects with the sound chamber 15. The diaphragm 16 is supported centrally below the throat, a rubber ring or diaphragm washer 17 being interposed between the marginal portion of the diaphragm and the under surface of the bell. The diaphragm is secured in place by the clamping ring 18 which is a heavy brass ring pressed against the under side of the peripheral portion of the diaphragm. The clamping ring is secured in place by means of clamping clips 19. These clips engage at their outer ends shelves 20 formed integrally with the bell, and at their inner ends with the clamping ring. The shelves 20 are provided with lips 21 for conveniencing assembly. The clips are secured in place by screws 22 which pass freely through holes in the clips and are screwed into screw holes

23 in the bosses 24 projecting downwardly 55 from the under side of the bell at uniform intervals around the bell. The receiver comprises the magnet 25 contained in the magnet-box 26. The magnet-box is screw-threaded on its outer side and adapted to be 60 screwed into the clamping ring 18 which is correspondingly threaded to receive it. The magnet is provided with two terminals 27 and 28 to which are attached the leading-in wires 29 and 30. The magnet-box is 65 provided with an adjusting arm 31 secured to the box and projecting downwardly and outwardly therefrom, as shown, and having its end turned upwardly outside the lower edge of the bell where it may be grasped by 70 the hand and moved in one direction or the other. By moving the lever to the right the magnet-box is screwed farther into the clamping ring, and the magnet is thereby 75 caused to be moved closer to the diaphragm; by movement in the opposite direction it is adjusted to a greater distance therefrom. In the position shown in Fig. 2 the magnet-box occupies the position of extreme adjustment of the magnet toward the diaphragm. 80 In order to prevent it from being adjusted closer than a certain predetermined distance from the diaphragm, and incidentally to prevent the magnet from being brought into contact with the diaphragm, the magnet-box, in assembling the parts, is screwed in until it occupies the position of closest desirable approach to the diaphragm, and then 85 the leather ring 12 is inserted in the groove in the under side of the lip of the bell with 90 its end 32 against the side of the arm 31, as shown in Fig. 2. The leather ring is made of such a length that its end 33 affords a stop for movement of the arm in the opposite direction, so that the magnet cannot be adjusted to a distance away from the diaphragm greater than that indicated when 95 the arm 31 comes into engagement with the end 33 of the leather ring 12.

In assembling this instrument the bell is 100 turned upside down, the rubber ring or diaphragm washer 17 is inserted and positioned by the bosses 24, the diaphragm 15 is laid on top of it, the clamping ring is 105 next inserted and centered with respect to the diaphragm; then the clips, which have previously occupied positions which would not interfere with the insertion of the rub-

ber ring, diaphragm and clamping ring, are now turned into approximately the position shown in Fig. 2, and the screws 22 are tightened so as thereby to secure the clamping ring and diaphragm in position. The magnet-box is now screwed into the clamping ring, and when it has been screwed into the position with the magnet in position of closest operable relation to the diaphragm 10 the leather ring 12 is inserted with the end 22 against the edge of the arm 31. The leading-in wires are then brought through the hole 34 and secured to the binding posts 27 and 28. The tie string 35 is tied to one 15 of the clips 19 in the usual fashion; then the apparatus is complete and ready for sale.

It will be observed that the sound chamber 15 is thin and flat and does not permit any reverberating sounds to be generated in 20 it when the apparatus is in operation. It will be observed that the rubber ring not only affords a good support for the diaphragm, but avoids the necessity of finishing the under side of the bell, the elasticity 25 of the rubber taking care of any inequalities. The clips are screwed down to hold the stiff clamping ring firmly in place, and the latter is made of such strength as to give adequate and rigid support to the edge of the 30 diaphragm. The adjustment of the magnet with relation to the diaphragm is easily secured without disturbance of the instrument by simply taking hold of the adjusting arm and moving it to the desired position. It is also seen that the arrangement 35 is such as to prevent bringing the magnet into accidental engagement with the diaphragm, which would not only be an adjustment incapable of use but would involve 40 the liability of permanent injury to the diaphragm. The leather ring in the lower edge of the bell affords a cushion support for the bell and prevents scratching the table or other support upon which the instrument may stand. It is to be further observed that the bell may be made of cast 45 iron and needs no machine work to finish it. The clips may be sheet iron stampings. The adjusting arm not only serves as the 50 means for adjusting the position of the magnet with relation to the diaphragm, but also by reason of its distortion to the position indicated in Fig. 1 it operates to hold the magnet-box in adjusted position. The instrument is cheap, easily manufactured and assembled, and it maintains its assembled 55 positions without liability of accidental misadjustment. It is provided with an adjustment for the magnet position having provision for preventing excessive adjustment either toward or from the diaphragm.

Having thus described the invention, what is claimed is:

1. A loud speaker having, in combination, a bell provided with a lip at the bottom, a receiver supported in the bell having a magnet and diaphragm and provided with an adjusting arm for adjusting the position of the magnet with relation to the diaphragm, such arm extending out under the edge of the bell, and stops for engaging the arm to prevent it from being moved excessively either in the direction to 65 limitedly adjust the magnet toward the diaphragm or in the opposite direction. 70

2. A loud speaker having, in combination, a bell provided with an upwardly-directed horn holder connected by a throat with the sound chamber, a receiver having a magnet and diaphragm secured to the inside of the bell opposite to the throat, the receiver being provided with an adjusting arm extending outwardly therefrom, the bell being provided at its lower edge with a lip under which the adjusting arm projects, such lip having a groove and being provided with a discontinuous cushion ring extending around the bottom of the bell and having its ends fixed with relation to the 80 adjusting arm to constitute stops therefor. 85

3. A loud speaker comprising a bell having a lip at its lower edge provided with a groove to receive a cushion ring, a receiver comprising a magnet-box containing a magnet, a clamping ring, the magnet-box and clamping ring being screw-threaded to afford adjustment of the position of the box with relation to the clamping ring, a diaphragm washer and diaphragm, the washer taking against the under side of the bell, the diaphragm against the washer, and the clamping ring against the diaphragm, and means for holding the clamping ring in place. 90

4. A loud speaker comprising a bell having a horn holder projecting upwardly therefrom and provided with a throat in the bell at the bottom of the horn holder entering into the bell chamber, a receiver comprising a magnet-box carrying a magnet, a clamping ring, a diaphragm and diaphragm washer, and means for clamping the clamping ring against the diaphragm and washer to hold the receiver in place, 110 consisting of a plurality of clips each consisting of a bar secured in place by a screw, the inside of the bell being provided with a series of shelves corresponding in number to the clips, and a plurality of bosses to receive the screws by which the clips are secured in place, the clips extending from the shelves to the clamping ring to hold the receiver in place. 115

In testimony whereof I have signed my name to this specification.

VERNON DURBIN.
